The ornamental design for a combined cassette player and stand for a framed picture, as shown and described.

DESCRIPTION

FIG. 1 is a front right perspective view of a combined cassette player and stand for a framed picture showing my new design;

FIG. 2 is a front elevational view thereof;

FIG. 3 is a left side elevational view thereof, the side opposite being a mirror image of the side shown;

FIG. 4 is a top plan view thereof;

FIG. 5 is a bottom plan view thereof; and,

FIG. 6 is a rear elevational view thereof.

The cord portion of the design is shown partially broken away to indicate indeterminate length; and the partially disclosed plug element is understood to have a conventional shape.

The broken line showing of the picture frame or the like is for illustrative purposes only and forms no part of the claimed design.
